UNITED STATES PATENT OFFICE.

GEORGE M. HENRIE, OF ST. LOUIS, MISSOURI.

IRONING BOARD.

Application filed October 22, 1921. Serial No. 509,594.

To all whom it may concern:

Be it known that GEORGE M. HENRIE, a citizen of the United States of America, residing at St. Louis, in the county of St. Louis and State of Missouri, has invented new and useful Improvements in Ironing Boards, of which the following is a specification.

The object of the invention is to provide an ironing board of the folding type adapted for attachment to the edge of a table or ledge, and particularly to provide a device of this type whereby an effective engagement of the clamping means with the table or ledge may be insured without injury to the latter, and whereby the elements of the structure may be readily adjusted to correspond with the height of the table top or ledge and the convenience of the operator; and with these objects in view the invention consists in a construction and combination of parts of which a preferred embodiment is shown in the accompanying drawings, wherein:—

Figure 1 is a side view partly broken away of an ironing board constructed in accordance with the invention.

Figure 2 is an inverted plan view of the same showing the leg standard in section.

Figure 3 is a detail view of the latch.

Figure 4 is a detail vertical sectional view through the swivel connection between the latch member and the jaw actuating rod.

The board 10 which obviously may be of any desired shape and dimensions is provided at its inner end with a clamp 11 consisting of jaws 12 adapted for movement toward and from the under surface of the adjacent end of the board to clamp therebetween the edge of a table top or shelf or ledge 13, said jaws being pivotally mounted upon and carried by arms 14 of a rock shaft 15. Also carried by said shaft is an arm 16 connected by a rod 17 with a latch 18 which is carried by the upper end of the leg or standard 19.

In the construction illustrated the jaws 12 and arms 14 with the connecting shaft constitute in effect a bell-crank lever mounted in the hanger portions 20 of the brackets 21 which are secured to the under surface of the ironing board.

The leg or standard 19 is adjustably connected with the latch 18 by means of an

attaching plate 22 which is slotted as shown 55 at 23 for engagement by the bolt 24 fitted with the thumb nut 25, and the pivotal mounting of the leg or standard upon the board to provide for the folding movement of the former with relation to the latter 60 is effected by providing the latch 18 with a fulcrum pin 26 which is terminally fitted in slots 27 in the side members 28 of a hanger also depending from the ironing board and carried by a suitable base plate 29. 65

The connection between the rod 17 and the latch is effected by means of a sleeve 30 mounted upon a pin 31 and constituting a guide through which the rod 17 extends, said rod carrying a coiled spring 32 seated 70 at one end against the sleeve and engaged at the other end by nut 33 which is threaded on the rod.

The latch when the leg or standard is in its normal or operative position is adapted 75 for engagement with a catch consisting of a shouldered seat 34 formed in the base plate 29.

In operation the clamp is arranged in the desired position with relation to the edge 80 of the table or ledge to which it is to be attached and the leg or standard is then swung from the dotted line position indicated in Figure 1 in the direction shown by the arrow to apply tension to the rod 17, 85 said leg or standard swinging on the center represented by the pin 26, until the leg or standard reaches an upright position whereupon an upward movement thereof will effect the engagement of the extremity of the 90 latch with the catch and thereby lock the parts in operative position. The leg or standard obviously will be held in the upright position by the engagement of the latch with the catch just as the clamp will be 95 held in proper engaging position by the same agency, under the yielding effect of the spring 32 of which the compression may be adjusted to suit the conditions and more particularly the thickness of the table top or 100 ledge 13 with which the clamp is engaged.

The swivel 30 will permit of the swinging movement of the latch with relation to the rod 17, and the latter may be provided as shown at 35 with the collar or stop for engagement by the sleeve when the leg or standard is in the folded position, to hold the clamp open or hold the jaws 12 spaced 105

from the plane of the board so as to facilitate the engagement of the device with the edge of the table top.

Having described the invention, what is claimed as new and useful is:—

1. An ironing board having a clamp for engaging the edge of a table top or ledge and including a movable jaw, a standard pivotally mounted for swinging movement into a plane parallel with the ironing board, a latch carried by the standard for engagement with a stationary catch when the standard is in its operative or supporting position, and a tensile connection between said latch and the movable jaw of the clamp yieldingly engaged with the former.
2. An ironing board having a clamp for engaging the edge of a table top or ledge and including a movable jaw, a standard pivotally mounted for swinging movement into a plane parallel with the ironing board, a latch carried by the standard for engagement with a stationary catch when the standard is in its operative or supporting position, and a tensile connection between said latch and the movable jaw of the clamp, the latch being fulcrumed upon a bracket depending from the board.
3. An ironing board having a clamp for engaging the edge of a table top or ledge

and including a movable jaw, a standard pivotally mounted for swinging movement into a plane parallel with the ironing board, a latch carried by the standard for engagement with a stationary catch when the standard is in its operative or supporting position, and a tensile connection between said latch and the movable jaw of the clamp and consisting of a rod extending through a guide on the latch, and a spring for positioning the rod with relation to the guide.

4. An ironing board having a clamp for engaging the edge of a table top or ledge and including a movable jaw, a standard pivotally mounted for swinging movement into a plane parallel with the ironing board, a latch carried by the standard for engagement with a stationary catch when the standard is in its operative or supporting position, and a tensile connection between said latch and the movable jaw of the clamp and consisting of a rod, a swivelled guide on the latch for directing said rod, and a compression spring arranged in bearing relation with the said guide.

In testimony whereof he affixes his signature.

GEORGE M. HENRIE.
